UNITED STATES PATENT OFFICE.

CHARLES M. HALL, OF DETROIT, MICHIGAN, ASSIGNOR TO C. M. HALL LAMP COMPANY, OF DETROIT, MICHIGAN, A CORPORATION OF MICHIGAN.

HEADLIGHT FOR VEHICLES.

1,087,168.

Specification of Letters Patent.

Patented Feb. 17, 1914.

Application filed March 22, 1909. Serial No. 484,997.

To all whom it may concern:

Be it known that I, CHARLES M. HALL, a citizen of the United States of America, residing at Detroit, in the county of Wayne 5 and State of Michigan, have invented certain new and useful Improvements in Headlights for Vehicles, of which the following is a specification, reference being had therein to the accompanying drawings.

10 The invention relates to headlights more particularly designed for use on automobiles and other vehicles, and consists in certain features of construction as hereinafter set forth.

15 In the drawings—Figure 1 is a vertical central longitudinal section through the headlight; Fig. 2 is a horizontal section thereof.

Headlights of the type to which my invention belongs are usually constructed to 20 distribute a portion of the light through a comparatively wide angle for the lighting of the immediate foreground, while another portion is concentrated within a limited 25 angle for long distance projection. The latter is useful where the vehicle is traveling at a comparatively high rate of speed—as for instance over a country road—but upon the crowded streets of a city it is objectionable on account of the blinding effect of 30 the light upon any one in its path.

It is therefore the principal object of the invention to provide means for diminishing the intensity of the light and particularly 35 that used for long distance projection.

It is a further object to accomplish this result with a simple attachment which may be applied to lights of standard construction.

40 As shown, A is the body of the lamp or lantern, which is provided with an inlet pipe B and burner C intended for acetylene or other gas or high illuminating power.

D is an annular reflector of parabolic 45 form arranged in the forward portion of the lantern for concentrating the light within the wide angle used for short range.

E is a concave reflector in rear of the light 50 for concentration within the limited angle for long distance projection.

My improvement consists essentially of a screen F which may be interposed between the burner and the reflector E, and which is 55 preferably formed of a translucent material permitting the passage of a portion of the

light, but greatly diminishing its intensity. For this purpose, I preferably employ sheets of mica, as they will have the desired diminishing effect, and are also well adapted to stand the heat concentrated thereupon. The 60 mica is held by a suitable annular frame G and preferably so that it may be easily removed or replaced, and also permitting of increasing or diminishing the number of sheets to vary the intensity of the transmitted 65 light. As shown, a split ring H engaging a groove in the frame is employed for holding the mica sheets. The frame G is adjustably supported by an arm I, and this, as shown, is swiveled upon the gas pipe B. 70 Thus a rotary adjustment is permitted, carrying the frame in one position into proximity to the reflector E, while rotating through a quarter turn will arrange the 75 screen at one side and out of the path of the rays from the reflector, as illustrated in dotted lines, Fig. 1.

In use, when the vehicle is traveling along the city streets, the screen may be adjusted, as shown in full lines in Fig. 1, and will 80 operate to deaden the reflection from the concave mirror E. When, however, the intense light for long distance projection is needed, it is only necessary to give the arm I a quarter turn, which will arrange the 85 screen out of the path of the rays.

What I claim as my invention is:

1. In a lamp, the combination with a source of light and a rearwardly positioned reflector, of a translucent screen adapted to 90 be interposed therebetween for dimming the intensity of the reflected light but out of the path of the forwardly projecting rays of unreflected light, said screen being adjustable to a position at the side of the lamp out 95 of the path of the light.

2. In a lamp, the combination with a body case, of a source of light therein, a rearwardly-positioned reflector, a translucent screen for dimming the light from said 100 source, and an arm carrying said screen rotatable in a horizontal plane to adjust the screen, said screen being arranged out of the path of the forwardly-projecting rays of light in one position of its adjustment, and 105 being interposed between the source of light and the reflector in the path of the reflected light, but out of the path of the forwardly-projecting rays of the unreflected light in another position of its adjustment. 110

3. In a lamp, the combination with a body case, of a vertically arranged burner therein for the source of light, a rearwardly-positioned reflector, a translucent screen, an arm extending laterally from and rotatable upon the burner carrying said screen, said screen being arranged in one position of adjustment of said arm out of the path of the forwardly-projecting rays of light, and in another position of adjustment being interposed between the reflector and the source of light in the path of the reflected light, but out of the path of the forwardly-projecting rays of the unreflected light.
- 15 4. The combination with a source of light

and a rearwardly-positioned reflector, of a translucent screen normally out of the path of the reflected light, said screen being movable to a position between said source of light and reflector for dimming the intensity of the reflected light, but out of the path of the forwardly projecting rays of unreflected light.

In testimony whereof I affix my signature in presence of two witnesses.

CHARLES M. HALL.
